UNITED STATES PATENT OFFICE.

STEPHEN W. BOURN, OF PROVIDENCE, RHODE ISLAND.

SOLE FOR RUBBER SHOES.

1,214,889.

Specification of Letters Patent. Patented Feb. 6, 1917.

Application filed December 4, 1914. Serial No. 875,526.

To all whom it may concern:

Be it known that I, STEPHEN W. BOURN, a citizen of the United States, and resident of the city of Providence, in the county of Providence and State of Rhode Island, have invented certain new and useful Improvements in Soles for Rubber Shoes, of which the following is a specification.

This invention relates to rubber boots and shoes and has for its object to provide an improvement in such boots and shoes for the purpose of reducing the cost of construction and increasing the wearing qualities. In this construction the outsole which comprises the forepart portion, the shank portion, the heel portion and the heel stay portion, is formed of one continuous homogeneous piece of stock, the heel base and stay portions of the continuous outsole being approximately of one and the same thickness and both being preferably formed much thinner than the ordinary heel portion. A lift is subsequently applied to the heel portion of the shoe of a quality different from that of the rest of the outsole.

Among the practical advantages of this construction are first:—

That by forming the heel portion thin the heel stay may be formed integral therewith which permits this part to be turned up and lapped around the lower portion of the upper about the heel, thereby reinforcing this portion and lending to it great strength and increasing the wearing quality of this portion of the shoe which is of particular advantage especially in ladies' shoes having heels of small sizes.

Second:—This construction avoids the necessity of forming this stay portion separately and subsequently attaching the same about the heel thus reducing the cost of construction.

Third:—This integral construction greatly improves the appearance of the finished shoe and does not detract from its graceful lines.

Fourth:—By forming the base of the heel portion thin a lift of rubber of a quality better than the rest of the outsole may be subsequently attached to the heel to receive the excess wear which this portion is always called upon to withstand and at the same time the attaching of this lift to this base portion does not excessively thicken the heel to detract from its neat appearance, but rather gives to the same the appearance of

having its outsole formed of one continuous piece.

Fifth:—The cost of the stock saved in this heel base portion may be applied to an extra quality lift thereby producing a shoe of greater wearing qualities with the same or less expense as produced by the old construction.

With these and other objects in view, the invention consists of certain novel features of construction, as will be more fully described, and particularly pointed out in the appended claims.

In the accompanying drawings:

Figure 1— is a side elevation of a shoe showing my improved outsole with the heel stay portion formed integral with the heel.

Fig. 2— is a plan view of the outsole as cut from sheet stock with the heel stay portion formed integral therewith.

Fig. 3— is a sectional view of the outsole showing the relative thickness of the different portions thereof and showing the heel base portion as recessed and made thinner than the shank portion.

Fig. 4— is a perspective view showing a heel lift which is formed separate from the outsole of a better quality of material to be subsequently attached to the heel portion.

Fig. 5— is a sectional view showing the lift formed at the forward edge of the heel base portion.

Fig. 6— is the same as Fig. 5 showing the heel lift attached.

In practice the wearing life of a rubber shoe is practically limited to the resisting quality of the heel portion, as this portion is called upon to receive by far the greater percentage of the wear. Then again it is found, particularly in the construction of ladies' rubber boots and shoes having small sized heels, to be very necessary to provide a heel stay portion to prevent the sharp edge of the small leather heel from cutting through the sides of the rubber shoe. It is also found in the practical construction of this outsole, to be of considerable advantage to form this stay portion integral with the heel portion.

In carrying out my invention I form the forepart portion 10, the shank portion 11, the heel base portion 12 and the heel stay portion 13 all of one integral continuous and homogeneous piece of material, but in such a construction it would be quite im-

practical to form a stay portion 13 of the required thinness and integral with the heel portion 12 if the latter were of the ordinary or usual thickness, owing to manufacturing difficulties, therefore, in order to form this stay portion integral with the heel portion I have reduced the thickness of the heel portion to substantially that of the stay portion or thinner thereby providing what might be termed a heel base portion and have attached to this thin base portion a lift 14 of a higher quality of rubber than the rest of the outsole. Then again in order to, in a measure, cover up the joint of union between the heel base and lift, and cause the whole when finished to present the appearance of one continuous homogeneous outsole, I have formed a lip or raised edge 15 at the forward edge of the heel portion 20 against which the forward edge of the lift sets, which latter edge is also beaded and slightly undercut at 16 to overlap this lip thus completely breaking the joint at that point. Then again it is found in practice that this raised lip serves to effectually protect the lift and prevent it from being broken from its fastening by being kicked or stubbed while in use.

By this construction it will be seen that I have obtained several distinct and important advantages, among others being First:—That the stay portion is formed integral with the heel portion, which when folded up and formed into position about the heel of the shoe, greatly strengthens the same over a construction in which the stay piece is formed separate and subsequently attached thereto, and this construction does not detract from the beauty or graceful lines of the shoe.

Then again by forming a thin heel base portion, an independent lift of better quality may be attached thereto, which will greatly improve the wearing life of the shoe and the cost saved in forming a thin heel

portion may be added to that of the lift thus increasing the wearing life of the shoe without increasing the cost of the same and as the base of the heel portion is formed very thin the addition of a second or outer lift 50 of better quality will not look thick, heavy or clumsy, but will be in keeping with the rest of the shoe and not detract from its general appearance.

Third:—By the provision of a raised lip 55 at the forward edge of the heel base and the over-lapping of the abutting edge of the lift at this point the joint is quite successfully hidden and the whole outsole has the appearance of a one-piece homogeneous construction.

I claim:

1. An outsole for a rubber boot or shoe, comprising a forepart portion, a shank portion, a heel base portion and a heel stay portion, all made of a single continuous sheet of rubber compound without joint or seam, the heel and stay portions being formed thinner than the forepart portion, and a heel lift of a quality different from that of the outsole attached to said heel base portion.

2. An outsole for a rubber boot or shoe, comprising a forepart portion, a shank portion, a heel base portion and a heel stay portion, all made of a single continuous sheet of rubber compound without joint or seam, the heel base and stay portions being formed thinner than the forepart portion, a lip raised at the forward edge of the heel base 75 portion, and a lift of different material from that of the outsole attached to the heel base portion with its forward edge abutting said lip.

In testimony whereof I affix my signature in presence of two witnesses.

STEPHEN W. BOURN.
